The Sketches offered to be these Setting Platine and making parts of the same
(returning) a description in the words of the late Edwin Keith of his
Improvement in the manufacture of glass for Cotton Prints

It is all to whom these present. Me a. come. It is known that it is more difficult
of propagation in the Country of Plymouth and that of C. May so a sword will be
presented a sword and a sword for the protection of the Manufacture of Cotton Goods
Country and that the following is a full and true description of the mode of manufacture
of cotton threads of spinning by me. I make the Cotton Goods in sheets
of the size above mentioned at the ends of coal iron or other iron wire, which will be
able for the purpose and as the part of the space is here the sheet will pass through
I introduce into the mouth before the melted metal is forced in, since
which of the stone thickness ^{and the} width of the space between the rods. Then this
may be made of cast iron wrought iron or of any material which will have
the effect to chill the metal suddenly when it comes in contact with it so
that when it is cast will have acquired the necessary hardness. Then
will a pattern of copper for the rods to have had the form of iron. I make
one in the heat and after those cast out these spaces between the iron rods
in the pattern of iron to the proper shape and mould it in common casting
stand and after casting during the time as before described the iron is very
hot. The stone object might be effective although at a greater distance by the
heat of the metal. Should one then striking the rods in any part of them make
any effort to break that part of the rods least exposed to heat which
in the common wrought iron rods as iron is small. Then as the metal passes
by it will be to the breaking of the rods in Cotton Goods & cast iron or other
iron wire which is for the purpose in sheets of the size above mentioned at the
ends and of chilling them either in water or in part as described above.
